REFORMING OF NAPHTHENES

John Walter Alliston, Christian Andreas Hansen, Jr., Harold Clayton Nix, and Donald Raymond Riggs, all of Baytown, Tex., assignors, by mesne assignments, to Esso Research and Engineering Company, Elizabeth, N.J., a corporation of Delaware

Filed July 22, 1958, Ser. No. 750,143

7 Claims. (Cl. 208—65)

The present invention is directed to reforming of hydrocarbons. More particularly, the invention is directed to the reforming of naphthenic hydrocarbons. In its more specific aspects, the invention is directed to a method for increasing yields and lowering the temperature drop in the adiabatic reforming of a naphthenic hydrocarbon.

The present invention may be briefly described as a method for increasing yields and lowering temperature drop in the adiabatic reforming of a naphthenic hydrocarbon boiling in the range from about 160° to about 380° F. in which there is added to the naphthenic hydrocarbon from about 10% to about 200% by volume of an aromatic hydrocarbon boiling in the range from about 260° F. to about 400° F. to provide an aromatic hydrocarbon content in the range from about 20% to about 65% by volume. The naphthenic hydrocarbon containing the added aromatic hydrocarbon is then reformed in an adiabatic reforming zone in the presence of a catalyst at a temperature in the range from about 700° to about 1000° F. Thereafter there is obtained from the reforming zone increased yields of reformed product of high octane number.

The present invention may be further illustrated by reference to the drawing in which:

Fig. 1 is a flow diagram of a preferred mode of practicing the invention and

Fig. 2 is a flow diagram of a modified mode of Fig. 1. Referring now to the drawing and particularly to Fig. 1, numeral 11 designates a feed line through which a virgin naphtha having a boiling range from about 160° to about 380° F. is introduced into a catalytic reforming zone 12, which is shown in diagrammatic form and into which hydrogen is introduced by way of line 13. It is understood that reforming zone 12 may include a plurality of adiabatic reforming zones which may be serially interconnected with means for heating between the several reaction zones and which may be 3 to 5 in number. For purposes of this description, reforming zone 12 may contain a platinum on alumina catalyst.

The reformed product from zone 12 is discharged therefrom by line 14 into a distillation zone 15 which is provided with a suitable internal vapor-liquid contacting means such as bell cap trays and other packing and the like to insure intimate contact between vapors and liquids. Zone 15 may be a single distillation tower equipped with a heating means such as steam coil 16 or may be a plurality of distillation towers, each equipped with means for inducing reflux and other auxiliary equipment such as condensing and cooling means, and the like. Zone 15 is provided with line 17 for discharge of reformed product and with line 18 for withdrawal of heavier fractions. Line 19, controlled by valve 20, is also provided for withdrawing a heavy aromatic hydrocarbon for recycle to line 11 by way of line 21. Makeup hydrocarbon may be introduced into line 11 by opening valve 22 in line 21. By virtue of lines 19 and 21, a suitable

2

amount of heavy aromatic hydrocarbon is provided in the feed to reforming zone 12.

Referring now to Fig. 2, another mode of providing heavy aromatic hydrocarbon is described in which there is introduced by way of line 25 into reforming zone 26 a virgin naphtha to which is added by way of line 27 from a source which will be described further a suitable xylene isomer which will comprise C₈ aromatic hydrocarbons. Hydrogen is introduced into zone 26 by line 28 and the reformed product is discharged from zone 26 by line 29 into a distillation and extraction zone 30 which may include distillation facilities such as described with respect to zone 15 or solvent extraction facilities or a combination of distillation and extraction facilities. Zone 30 may be considered as a separation zone for discharge and recovery of desirable products and to separate a xylene fraction. Therefore, zone 30 is provided with line 31 for recovery of toluene and lighter hydrocarbons, line 32 for discharge of C₈ and heavier hydrocarbons, including aromatics, while line 33 is provided for withdrawal of a C₈ concentrate fraction containing xylene isomers. Zone 30 is provided with a heating means illustrated by a steam coil 30a.

Line 33 introduces the xylene concentrate to a xylene separation zone 34 which may be a crystallization zone or a combination of distillation and crystallization. The crystallization, which may take place in zone 34, may operate at a temperature in the range from -65° to -105° F. to separate a purified xylene isomer such as paraxylene by way of line 35. If separation zone 34 includes a distillation zone, line 35 may also serve to withdraw orthoxylene as may be desired. There are separated from zone 34 by line 36 other xylene isomers which may include ethyl benzene, metaxylene, and the like, either in purified condition or as a mixture of xylene isomers, which may be discharged, at least in part, from the system by opening valve 37. A portion of the xylene isomer or isomers in line 36 are recycled by way of line 27, controlled by valve 38 to line 25 to provide the concentration of aromatics in the feed in line 25 to the reforming zone 26. Under some conditions orthoxylene may be returned to zone 26 to provide the desired amount of aromatic hydrocarbon.

By virtue of providing an added aromatic hydrocarbon in the feed to a reforming zone such as 12 and 26, cracking of the naphthenic hydrocarbon feed to gas and coke is suppressed. By charging a substantially pure heavy aromatic hydrocarbon with the naphthenic feed to a catalytic reforming operation, the yield of desirable product of high octane number from the reforming operation is higher than that which would be obtained without the added heavy aromatic hydrocarbon. The recycle stream of heavy aromatic hydrocarbon not only allows an increase in yield but reduces the temperature drop across the adiabatic reforming zones of such an operation and permits the obtaining of conditions which approach the ideal isothermal state.

In the practice of the present invention, the added heavy aromatic hydrocarbon may be obtained from an extraneous source in part or may be obtained, at least in part, from within the system by fractionally distilling the product and recycling a selected heavy aromatic hydrocarbon. Likewise the product may be distilled and/or solvent extracted and further purified to obtain the desired substantially purified heavy aromatic hydrocarbon.

In order to illustrate the advantages inuring to the practice of the present invention, a comparison of the yields obtained with and without the added aromatic hydrocarbon is set out in Table I.

3
Table I

	Run 1	Run 2
C ₅ + Research Octane Number on Virgin Feed		
Hydroformate	100.1	99.9
Feed Rate, Bbl./Day	15,000	16,860
Heavy Aromatic Added, Percent by volume	0	11.3
Max. Temperature, ° F.	935	938
Material Balance (Percent of Fresh Feed):		
C ₅ + Yield	76.56	80.13
C ₄	4.26	3.62
nC ₄	4.57	3.96
Fuel Gas	14.66	13.26
Loss	(0.05)	(0.97)

From the comparison in Table I in which run No. 1 represents conventional practice and run No. 2 the present invention, it will be clear that the C₅+ yield has been substantially appreciated over the conventional operation while obtaining a product of substantially the same research octane number.

In order to further illustrate the practice of the present invention, there is presented in Table II distillation characteristics of typical feedstocks to the present invention and the distillation characteristics of the added aromatic hydrocarbon along with analyses of the feedstocks and added aromatic hydrocarbon.

Table II

	Typical Feedstock	Feedstock Employed	Added Aromatics
Gravity, ° API	55.5	53.3	31
Distillation:			
15° F., ° F.	185	222	278
5% at	208	225	
10% at	229	225	
20% at	244	227	
30% at	258	229	
40% at	268	231	
50% at	280	233	
60% at	290	236	
70% at	301	240	
80% at	316	245	
90% at	331	255	
95% at	353	263	
FBP, ° F.	375	296	
DP, ° F.	366	278	290

MASS SPECTROMETER ANALYSIS, PERCENT BY VOLUME

	0.0	0.0	0.0
Benzene	0.0	0.0	0.2
Toluene	4.0	10.0	
C ₈ Aromatics	5.5	7.9	95.0
C ₉ Aromatics	4.0	0.3	2.5
C ₁₀ Aromatics	1.5	0.0	0.0
Total Aromatics	15.0	18.2	97.7
Olefins	1.0	1.0	0.0
Naphthenes	45.0	50.5	0.7
Paraffins	39.0	30.3	1.6
	100.0	100.0	100.0

From Table II, it will be clear that an aromatic hydrocarbon containing approximately 98% aromatics may be satisfactorily used and that the feedstocks may contain up to about 18.2% of aromatics which are normally contained in the virgin feed. In the practice of the present invention where about 10% to about 200% of aromatic hydrocarbons are added to the virgin feed, it is desirable to increase the aromatic hydrocarbon content to about 20 to about 65 volume percent. The virgin feed may normally contain from about 5 to about volume percent of aromatic hydrocarbon.

The present invention not only serves to increase the yields in the adiabatic reforming of naphthenic hydrocarbons but the temperature drops across the reactors of the adiabatic reforming zone are substantially less with the added aromatic hydrocarbon than without the added aromatic hydrocarbon. As exemplary of the advantages of the present invention, there is set out in Table III a comparison of temperature drops in three reaction zones wherein the first column shows operations without added

4
aromatics and the second column shows operations with added aromatics.

Table III

5	Temperature Drop	
	° F. without Added Aromatics	° F. With Added Aromatics
10		
1st Reactor	175	160
2nd Reactor	125	100
3rd Reactor	70	30

From Table III it will be clear that the temperature drop in the first reactor has been decreased from 175° to 160° F. while in the second reactor the temperature drop has been decreased from 125° to 100° F. while in the third reactor the temperature drop has been decreased from 70° to 30° F. These temperature drop decreases are substantial and allow obtaining of substantially improved results.

The purity of the added or recycled aromatic hydrocarbon is from about 70 to about 100 percent aromatics. However, best results are obtained with a purity of the purified aromatic hydrocarbon in the range from about 90 to about 100 percent.

The boiling range of the added aromatic hydrocarbon depends on the boiling range of the virgin feed naphtha. In general, it is desirable that the molecular weight of the added aromatic hydrocarbon be kept to a minimum to reduce disproportionation and other undesirable side reactions which may involve the added aromatic hydrocarbon. For example, with a virgin feed naphtha having an end point in the range of 230° to about 270° F. the added aromatic hydrocarbon should be substantially xylenes. For a virgin feed naphtha having end point of 290° to about 305° F. a mixture of C₈ aromatic hydrocarbons could be used and for heavier feed naphthas C₁₀ and C₁₁ aromatics are desirable. The selection of the aromatic hydrocarbon with the desired end point permits separation by distillation for recycling as may be desired. The separation may be obtained by distillation or extraction or a combination of distillation and extraction to obtain the recycle aromatic of the desired end point. It is preferred to separate the aromatic for recycling by distillation.

In reforming the naphthenic hydrocarbon, temperatures may be in the range from about 700° to about 1000° F. with preferred operations from about 700° to about 985° F. Operations have been satisfactorily conducted at 800° to 938° F.

Pressures may suitably range from about 100 to about 500 p.s.i.g. with a preferred pressure range from about 200 to about 350 p.s.i.g. Operations have been satisfactorily conducted at from about 200 to about 245 p.s.i.g.

Space velocities may range from about 0.5 to about 6.0 v./v./hr. with a preferred range from about 0.5 to about 2 v./v./hr. with actual operations having been conducted at 1.3 v./v./hr.

The catalyst is preferably a platinum on alumina catalyst which may contain about 0.1 to 0.6 percent by weight of platinum with a preferred range of 0.3 to about 0.6 percent by weight. Satisfactory operations have been conducted at 0.6% by weight platinum on alumina catalyst.

While the support is preferably alumina, it may be purified alumina such as gamma alumina, other supports such as magnesia, zirconia, and the like may be used.

Likewise, while a platinum catalyst is preferred, the invention may be suitably operated with a molybdenum oxide catalyst on a suitable support. For example, molybdena on gamma alumina may be satisfactory. Other reforming catalysts which are well known in the art may be used.

The amount of hydrogen employed may range from about 500 to about 6,000 standard cubic feet per barrel of total charge. Satisfactory operations have been obtained at about 3,000 standard cubic feet per barrel of total charge.

The present invention is quite advantageous and useful in a commercial operation, has resulted in about 5 percent less coke formation and has reduced light gas production about 10 percent as compared with charging a virgin feed naphtha alone to an adiabatic reforming zone. Besides reducing coke formation and light gas formation, an increase in yield of about 2.5 percent by volume is obtained when the virgin feed is reformed at the same severity as measured by Research Octane number of the reformed product.

The invention is, therefore, quite advantageous and useful.

The nature and objects of the present invention having been completely described and illustrated, what we wish to claim as new and useful and secure by Letters Patent is:

1. A method for increasing yields and lowering temperature drop in the adiabatic reforming of a naphthenic hydrocarbon boiling in the range from about 160° F. to about 380° F. containing from about 5 to about 18% by volume of aromatic hydrocarbon which comprises adding from about 10% to about 200% by volume of a C₈ to C₁₁ aromatic hydrocarbon containing from about 70% to about 100% aromatics and boiling in the range from about 260° F. to about 400° F. to said naphthenic hydrocarbon to provide an aromatic hydrocarbon content in the range from about 20% to about 65% by volume, then adiabatically reforming said naphthenic hydrocarbon containing said added aromatic hydrocarbon in an adiabatic reforming zone in the presence of hydrogen and a platinum reforming catalyst at a temperature in the range from about 700° to about 1000° F., and recovering from said zone increased yields of reformed product.

2. A method for increasing yields and lowering temperature drop in the adiabatic reforming of a naphthenic hydrocarbon boiling in the range from about 160° F. to about 380° F. containing from about 5 to about 18% by volume of aromatic hydrocarbon which comprises adding from about 10% to about 200% by volume of a substantially purified C₈ to C₁₁ aromatic hydrocarbon boiling in the range from about 260° F. to about 400° F. to said naphthenic hydrocarbon to provide an aromatic hydrocarbon content from about 20% to about 65% by volume, then adiabatically reforming said naphthenic hydrocarbon containing said added aromatic hydrocarbon in a plurality of adiabatic reforming zones in the presence of hydrogen and a platinum catalyst at a temperature in the range from about 700° to about 1000° F., and recovering from said zones increased yields of reformed product.

3. A method in accordance with claim 2 in which the purified aromatic hydrocarbon is xylene.

4. A method in accordance with claim 2 in which the purified aromatic hydrocarbon comprises C₉ hydrocarbons.

5. A method for increasing yields and lowering temperature drop in the adiabatic reforming of a naphthenic hydrocarbon boiling in the range from about 160° F. to about 380° F. containing from about 5 to about 18% by volume of aromatic hydrocarbon which comprises adding from about 10% to about 200% by volume of a substantially purified C₈ to C₁₁ heavy aromatic hydrocarbon to said naphthenic hydrocarbon to provide an aromatic hydrocarbon content from about 20% to about 65% by volume, then adiabatically reforming said naphthenic hydrocarbon containing said added aromatic hydrocarbon in an adiabatic reforming zone in the presence of hydrogen and a supported platinum catalyst at a temperature in the range from about 700° to about 1000° F., recovering from said zone increased yields of reformed product, separating from said recovered reformed product reformed gasoline and substantially purified heavy aromatic hydrocarbon boiling in the range from about 260° F. to about 400° F., and recycling said substantially purified heavy aromatic hydrocarbon for addition to said naphthenic hydrocarbon.
- 10 6. A method in accordance with claim 5 in which the reformed gasoline and substantially purified heavy aromatic hydrocarbon are separated from the recovered reformed product by distillation.
- 15 7. A method for increasing yields and lowering the temperature drop in the adiabatic reforming of a naphthenic hydrocarbon boiling in the range from about 160° F. to about 380° F. containing from about 5 to about 18% by volume of aromatic hydrocarbon which comprises adding from about 10% to about 200% by volume of xylene to said naphthenic hydrocarbon to provide an aromatic hydrocarbon content in the range from about 20% to about 65% by volume, then adiabatically reforming said naphthenic hydrocarbon containing said added xylene in an adiabatic reforming zone in the presence of hydrogen and a platinum reforming catalyst at a temperature in the range from about 700° to about 1000° F., recovering from said zone increased yields of reformed product, distilling and extracting said reformed product to form a xylene fraction, separating from said xylene fraction a first selected isomer and a second selected isomer and recycling one of said selected isomers for adding to said naphthenic hydrocarbon as said added xylene.
- 20 8. A method for increasing yields and lowering the temperature drop in the adiabatic reforming of a naphthenic hydrocarbon boiling in the range from about 160° F. to about 380° F. containing from about 5 to about 18% by volume of aromatic hydrocarbon which comprises adding from about 10% to about 200% by volume of xylene to said naphthenic hydrocarbon to provide an aromatic hydrocarbon content in the range from about 20% to about 65% by volume, then adiabatically reforming said naphthenic hydrocarbon containing said added xylene in an adiabatic reforming zone in the presence of hydrogen and a platinum reforming catalyst at a temperature in the range from about 700° to about 1000° F., recovering from said zone increased yields of reformed product, distilling and extracting said reformed product to form a xylene fraction, separating from said xylene fraction a first selected isomer and a second selected isomer and recycling one of said selected isomers for adding to said naphthenic hydrocarbon as said added xylene.
- 25 9. A method for increasing yields and lowering the temperature drop in the adiabatic reforming of a naphthenic hydrocarbon boiling in the range from about 160° F. to about 380° F. containing from about 5 to about 18% by volume of aromatic hydrocarbon which comprises adding from about 10% to about 200% by volume of xylene to said naphthenic hydrocarbon to provide an aromatic hydrocarbon content in the range from about 20% to about 65% by volume, then adiabatically reforming said naphthenic hydrocarbon containing said added xylene in an adiabatic reforming zone in the presence of hydrogen and a platinum reforming catalyst at a temperature in the range from about 700° to about 1000° F., recovering from said zone increased yields of reformed product, distilling and extracting said reformed product to form a xylene fraction, separating from said xylene fraction a first selected isomer and a second selected isomer and recycling one of said selected isomers for adding to said naphthenic hydrocarbon as said added xylene.
- 30 10. A method for increasing yields and lowering the temperature drop in the adiabatic reforming of a naphthenic hydrocarbon boiling in the range from about 160° F. to about 380° F. containing from about 5 to about 18% by volume of aromatic hydrocarbon which comprises adding from about 10% to about 200% by volume of xylene to said naphthenic hydrocarbon to provide an aromatic hydrocarbon content in the range from about 20% to about 65% by volume, then adiabatically reforming said naphthenic hydrocarbon containing said added xylene in an adiabatic reforming zone in the presence of hydrogen and a platinum reforming catalyst at a temperature in the range from about 700° to about 1000° F., recovering from said zone increased yields of reformed product, distilling and extracting said reformed product to form a xylene fraction, separating from said xylene fraction a first selected isomer and a second selected isomer and recycling one of said selected isomers for adding to said naphthenic hydrocarbon as said added xylene.
- 35 11. A method for increasing yields and lowering the temperature drop in the adiabatic reforming of a naphthenic hydrocarbon boiling in the range from about 160° F. to about 380° F. containing from about 5 to about 18% by volume of aromatic hydrocarbon which comprises adding from about 10% to about 200% by volume of xylene to said naphthenic hydrocarbon to provide an aromatic hydrocarbon content in the range from about 20% to about 65% by volume, then adiabatically reforming said naphthenic hydrocarbon containing said added xylene in an adiabatic reforming zone in the presence of hydrogen and a platinum reforming catalyst at a temperature in the range from about 700° to about 1000° F., recovering from said zone increased yields of reformed product, distilling and extracting said reformed product to form a xylene fraction, separating from said xylene fraction a first selected isomer and a second selected isomer and recycling one of said selected isomers for adding to said naphthenic hydrocarbon as said added xylene.
- 40 12. A method for increasing yields and lowering the temperature drop in the adiabatic reforming of a naphthenic hydrocarbon boiling in the range from about 160° F. to about 380° F. containing from about 5 to about 18% by volume of aromatic hydrocarbon which comprises adding from about 10% to about 200% by volume of xylene to said naphthenic hydrocarbon to provide an aromatic hydrocarbon content in the range from about 20% to about 65% by volume, then adiabatically reforming said naphthenic hydrocarbon containing said added xylene in an adiabatic reforming zone in the presence of hydrogen and a platinum reforming catalyst at a temperature in the range from about 700° to about 1000° F., recovering from said zone increased yields of reformed product, distilling and extracting said reformed product to form a xylene fraction, separating from said xylene fraction a first selected isomer and a second selected isomer and recycling one of said selected isomers for adding to said naphthenic hydrocarbon as said added xylene.
- 45 13. A method for increasing yields and lowering the temperature drop in the adiabatic reforming of a naphthenic hydrocarbon boiling in the range from about 160° F. to about 380° F. containing from about 5 to about 18% by volume of aromatic hydrocarbon which comprises adding from about 10% to about 200% by volume of xylene to said naphthenic hydrocarbon to provide an aromatic hydrocarbon content in the range from about 20% to about 65% by volume, then adiabatically reforming said naphthenic hydrocarbon containing said added xylene in an adiabatic reforming zone in the presence of hydrogen and a platinum reforming catalyst at a temperature in the range from about 700° to about 1000° F., recovering from said zone increased yields of reformed product, distilling and extracting said reformed product to form a xylene fraction, separating from said xylene fraction a first selected isomer and a second selected isomer and recycling one of said selected isomers for adding to said naphthenic hydrocarbon as said added xylene.
- 50 14. A method for increasing yields and lowering the temperature drop in the adiabatic reforming of a naphthenic hydrocarbon boiling in the range from about 160° F. to about 380° F. containing from about 5 to about 18% by volume of aromatic hydrocarbon which comprises adding from about 10% to about 200% by volume of xylene to said naphthenic hydrocarbon to provide an aromatic hydrocarbon content in the range from about 20% to about 65% by volume, then adiabatically reforming said naphthenic hydrocarbon containing said added xylene in an adiabatic reforming zone in the presence of hydrogen and a platinum reforming catalyst at a temperature in the range from about 700° to about 1000° F., recovering from said zone increased yields of reformed product, distilling and extracting said reformed product to form a xylene fraction, separating from said xylene fraction a first selected isomer and a second selected isomer and recycling one of said selected isomers for adding to said naphthenic hydrocarbon as said added xylene.
